US00D753658S

(12) **United States Design Patent**
Zuccarino et al.

(10) **Patent No.:** US D753,658 S
(45) **Date of Patent:** ** *Apr. 12, 2016

(54) **DISPLAY DEVICE WITH CAMERAS**

(71) Applicant: **Aquifi, Inc.**, Palo Alto, CA (US)

(72) Inventors: **Tony Zuccarino**, Saratoga, CA (US);
Abbas Rafii, Palo Alto, CA (US)

(73) Assignee: **Aquifi, Inc.**, Palo Alto, CA (US)

(*) Notice: This patent is subject to a terminal disclaimer.

(**) Term: **14 Years**

(21) Appl. No.: **29/480,802**

(22) Filed: **Jan. 29, 2014**

Related U.S. Application Data

(63) Continuation-in-part of application No. 13/987,323, filed on Jan. 29, 2013, now abandoned.

CLAIM

The ornamental design for a display device with cameras, as shown and described.

DESCRIPTION

FIG. 1 is a perspective view of a display device with cameras in accordance with our design wherein the display is shown applied to an unclaimed laptop computer;
FIG. 2 is a front view thereof;

FIG. 3 is a perspective view thereof wherein the display is shown applied to an unclaimed computer monitor;

FIG. 4 is a front view thereof;

FIG. 5 is a perspective view thereof wherein the display is shown applied to an unclaimed all-in-one computer;

FIG. 6 is a front view thereof;

FIG. 7 is a perspective view thereof wherein the display is shown applied to an unclaimed tablet computer; and,

FIG. 8 is a front view thereof.

Broken lines shown in the drawings are for environment only, and form no part of the claimed design.

1 Claim, 8 Drawing Sheets
